UNITED STATES PATENT OFFICE.

JESSE A. CRANDALL, OF BROOKLYN, NEW YORK.

CHILD'S CARRIAGE.

SPECIFICATION forming part of Letters Patent No. 323,401, dated August 4, 1885.

Application filed May 25, 1885. (No model.)

To all whom it may concern:

Be it known that I, JESSE A. CRANDALL, a citizen of the United States, residing at the city of Brooklyn, in the county of Kings and State of New York, have invented a new and useful Improvement in Canopies for Children's Carriages; and I do hereby declare that the following specification, taken in connection with the drawings annexed to and forming part of the same, furnishes a full and clear description thereof, sufficient to enable those skilled in the art to which it pertains to make and operate the same.

The objects of my invention are to provide children's carriages with a shade or canopy which shall be light and simple in construction, and yet be strong and durable; be capable of easy adjustment and removal when occasion requires, and which shall be not only a protection to the occupant of the carriage from the rays of the sun, but also an effective barrier and shield against wind, rain, and dust. I attain these objects by the use of the device and construction illustrated in the accompanying drawings, in which—

Figure 1 is a view of a child's carriage with my improved canopy attached thereto. Fig. 2 is a view of the cross-bars and rods which support the canopy; and Fig. 3 is a view of one of the cross-bars.

In the drawings, A is the body of a child's carriage, constructed of any desired material suitable for that purpose.

B is the canopy, in the construction of which any desired and suitable textile fabric or fabrics may be employed, and which may be extended downward on the sides of the carriage to any desired point to form side curtains.

C C are parallel metallic rods attached to the body of the carriage at or near the rear end thereof and extending upward and curving forward parallel with each other, over the carriage-body, to form the support for the canopy B and its cross-bars D D.

D D are adjustable cross-bars, which may be constructed of wood or of metal, as desired, and which have apertures, a a, near their extremities, into and through which apertures the metallic rods C C are inserted and pass, allowing such cross-bars, when it is so desired, to be moved freely either backward or forward

over and upon said rods C C. The canopy B is attached to said cross-bars D D by tacks b b, or in any other suitable manner. 55

E E and F F are thumb-screws, the office of which is to hold the cross-bars D D in place in any desired location upon the said rods C C.

G G are supports for the lower extremities 60 of the rods C C, and may be fixed in any desired and suitable location upon the carriage at or near the rear end of the body thereof. Each of said supports G G has a socket, c, into which the respective lower extremities of 65 the rods C C are inserted, and a thumb-screw, H, to hold said extremities of said rods firmly in place in said supports G G.

Similar letters refer to similar parts throughout the several views. 70

Having thus described the several parts of my said invention, and having attached the canopy B to the cross-bars D D, as described, and having provided said cross-bars D D with the thumb-screws E E and F F, I attach my 75 said invention and improvement to a child's carriage as follows: I secure the supports G G, each having the socket c and thumb-screw H, to the carriage at or near the rear end of the body thereof, and loosen the thumb-screw H. 80 Into one of the sockets c c of the supports G G, I insert the lower extremity of one of the rods C C and then tighten the thumb-screw H. The other rod, C, is then inserted in and secured to the other support, G, in a similar manner. 85 The rods C C, when so placed and secured, extend upward and curve forward parallel with each other over the carriage-body. I then slip the cross-bars D D, which have secured upon them the canopy B and the thumb-screws 90 E E and F F, (said thumb-screws being loosened,) upon the rods C C by passing the respective upper extremities of said rods C C through the apertures a a, near the extremities of said cross-bars D D. When all of said 95 cross-bars have been so slipped upon said rods, I arrange the canopy B in any desired position, and tighten the thumb-screws E E and F F; the canopy is then held firmly in place upon the rods C C. 100

When it is desired to remove the canopy and the rods from the carriage, the thumb-screws E E and F F are loosened, the cross-bars D D are slipped forward to the outer ex-

tremities of the rods C C and off from said rods. The thumb-screws H H of the supports G G are loosened, and the lower extremities of the rods C C are then removed from said 5 supports. The canopy and rods may then be packed in small compass until again needed for use.

By the use of my invention the occupant of the carriage is not only protected against the 10 rays of the sun, from whatever direction such rays may come, but is also shielded from wind, rain, and dust, and this more effectively and with greater dispatch than by any device in the nature of a canopy or shield for children's carriages now known or used. When 15 the rays of the sun strike vertically upon the carriage, or if rain falls in the same direction upon the carriage and it is desired to protect and shield the child therefrom, the thumb-screws E E at the front of the canopy B are 20 tightened, the thumb-screws F F at the rear of the canopy are loosened, the canopy is drawn down to the back of the seat of the carriage, the cross-bars D D moving freely over 25 the rods C C, and the thumb-screws F F are tightened. The canopy is then in the position shown in Fig. 1, and with its side curtains affords complete protection to the occupant of the carriage. When the sun's rays 30 strike the carriage at the rear thereof, or when wind, rain, or dust strike the rear of the carriage and fall upon or are blown upon and against the child, the canopy is arranged in the same position as above described, and the 35 child is as effectually shielded and protected. When the rays of the sun are directed into the front of the carriage and upon the child, or when wind, dust, or rain are blown upon or fall upon the child from the same direction, 40 the thumb-screws E E and F F are loosened, the canopy is drawn forward over the rods C C until the cross-bar which was at the rear of the carriage reaches the outer extremities of the rods C C; the thumb-screws F F are tightened, and the unsecured end of the canopy 45 is then carried forward to the dash-board or front of the carriage-body, and is attached thereto by hooks or in any other suitable manner. The canopy in this position, with 50 its side curtains, serves as a perfect barrier to the ingress of wind, rain, or dust, and prevents annoyance or discomfort therefrom to the occupant of the carriage. It is obvious that the same results would be obtained by 55 having the parallel rods C C, which extend over the carriage-body, branch from a single stem fastened at the back of the carriage without departing from the valuable feature of the invention, which is the provision of the parallel rods to firmly support and allow of the 60 adjustment of the canopy.

I am aware that a single rod has been used

to extend from the rear of the carriage to support at a single point an ordinary parasol-canopy; and I am also aware that divers devices have been made to extend up from the sides of the carriage for the purpose of shifting the canopy like an ordinary buggy-top. The former devices are only effective against the rays of the sun. The latter devices are 70 objectionable, as being liable to squeeze and injure the infant's fingers.

My invention, as above described, secures all the advantages of both the other methods of adjusting the canopy and of firmly supporting the canopy in any desired position.

Having thus particularly described my said invention and improvement, its construction, advantages, mode of use, and operation, what I claim, and desire to secure by Letters Pat- 80 ent, is—

1. In combination with the body of a child's carriage, the rods C C, running parallel with each other above the body of the carriage and adapted to support and accommodate the adjustments of the canopy, substantially as described.

2. A support for canopies of children's carriages, consisting of the rods C C, running parallel with each other above the carriage-body, 90 attached to the carriage at or near the rear of the body thereof by supports G G, having sockets c c and thumb-screws H H, the adjustable cross-bars D D, each having apertures a a near their extremities, and the 95 thumb-screws E E and F F, substantially as described, and for the purposes shown and described.

3. In combination with a child's carriage, the supports G G, parallel rods C C, adjustable cross-bars D D, and thumb-screws E E and F F, substantially as shown and described, and for the purposes described.

4. The thumb-screws E E and F F, adjustable cross-bars D D, and parallel rods C C, in 105 combination with a child's carriage, as and for the purposes described.

5. In canopies for children's carriages, the combination, with said carriage, of the supports G G, having sockets c c and thumb-screws H H, the parallel rods C C, adjustable cross-bars D D, and thumb-screws E E and F F, as and for the purposes shown and described.

6. The adjustable cross-bars D D, having 115 apertures a a near their extremities, in combination with the thumb-screws E E and F F, or their equivalents, and the canopy-rods C C of a child's carriage, as and for the purpose shown and described.
